in Great Britain July 7, 1931

8 Claims. (Cl. 140—71)

The invention relates to means for the manufacture of frames, particularly applicable for concrete reenforcement consisting of two parallel main bars and cross-wires or transverse bars wound at intervals between these main bars. Hitherto it has been customary to produce framework of this kind by winding the cross-wires round the two parallel bars by hand or by providing both ends of the cross-wires with coils for the accommodation of the bars by mechanical means and afterwards pushing the wires on to the bars. In the former case the construction of the reenforcements is tedious and expensive and, in addition, it is very difficult to keep the space between the two parallel bars exactly uniform throughout their length. In the latter case the mechanically produced coils of the cross-wires must have a larger inside diameter than the diameter of the parallel bars, so as to enable them to be pushed on to the bars. Apart from the tediousness of this process, it also involves the serious inconvenience that the cross-wires are not immovably fixed on the parallel bars and can be displaced slantwise, for example, when the concrete is being rammed.

It has already been proposed to coil the ends of the cross-wires round the parallel bars in the same direction by a machine which necessitated the use of a special device for each particular distance between the parallel bars.

This invention eliminates these inconveniences by the provision of a simple machine provided with two coiling heads surrounding guide sleeves through which the main bars are passed and rotated in opposite directions much in the same manner as obtained with the complicated machines at present in use for making wide wire fabrics with a large number of longitudinal wires and with cross wires coiled between them.

In the improved machine which constitutes the invention one sleeve is displaceable longitudinally in a guide formed in the machine casing and is provided with means for causing the driving gear to move with it in relation to the driving shaft. The displaceable sleeve is provided with a rod running parallel to the guide and is fitted with a handle for longitudinal adjustment and means for locking it in various positions.

Other features of the machine consist in the use of eccentrically mounted rollers in the coiling heads for engaging the wire to be coiled and liners to the sleeves to accommodate bars of varying diameter.

In the accompanying drawings which illustrate in diagrammatic manner a preferred embodiment of the invention,

Fig. 1 shows the apparatus in front elevation.

Fig. 2 is a section along the line 2—2 in Fig. 1.

Fig. 3 is a section along the line 3—3 in Fig. 1.

Figs. 4 and 5 show the sliding block serving as the bearing for one of the guide sleeves, in front elevation and in side elevation respectively.

Figure 6 illustrates the kind of frame which the machine is intended to make.

In a casing *a*, the rear wall *a*¹ of which is detachable and is held in position by bolts *b*, a shaft *c* is arranged. This shaft *c* is supported in the end walls of the casing *a*, which are provided with suitable bearing attachments *d*¹ and *d*², and carries a hand crank *e* on the end projecting from the casing. Inside the casing *a* the shaft *c* carries two worms or screw wheels *f*¹ and *f*², at a certain distance apart, which by means of feathers (keys) *g*¹ and *g*² are driven by the shaft in the direction of rotation. One worm wheel *f*², is—for a purpose which shall be explained in more detail later—arranged so as to be displaceable with its feather *g*² in a longitudinal groove *c*¹ of the shaft *c*. The two worms or screw wheels *f*¹ and *f*² engage with two worm wheels or screw wheels *h*¹ and *h*² fixed on two rotatable sleeves or bushes *i*¹, *i*² and arranged underneath the shaft *c* with axes at right angles to the axis of the shaft *c*. The worm or screw-threads of the wheels *f*¹, *h*¹ pitch in opposite directions to the worm or screw-threads of the wheels *f*², *h*², so that by turning the shaft *c* by means of the hand crank *e* the two sleeves or bushes *i*¹, *i*² are rotated in opposite directions.

The sleeve *i*¹ is carried in a fixed bearing attachment *k* of the casing *a*, while the sleeve *i*² is positioned in a special block consisting of two parts *l*¹, *l*², leaving between them grooves *l*³ which are displaceable in guides *m* arranged in the front wall of the casing *a*, parallel to the shaft *c*. The displacement of the block is ef-

fected by a rod l^3 acting thereon, which rod extends through a bearing attachment d^3 , serving as guide in the one end wall of the casing a , and is provided with a handle l^4 on the outer end. This rod l^3 is provided with several consecutive bore-holes l^5 which can on the displacement of the rod be brought consecutively into register with a bore-hole in the guide d^3 accommodating a pin or a screw l^8 , so that by means of the pin l^8 , the rod l^3 can be locked in various positions. Thus the sleeve i^2 can be adjusted at different distances from the sleeve i^1 . The sleeves i^1 and i^2 serve as guides for the parallel bars used for the manufacture of the reinforcements, which bars are to be connected to each other by means of cross-wires. The one sleeve i^1 contains a liner s , which is inserted loosely and can be changed for other liners of larger or smaller internal diameter. Also, both sleeves can be provided with such liners.

Inside the casing a the block l^1 , l^2 is fitted with an upper limb n which engages in an annular groove of the extended boss f^3 of the worm or screw-wheel f^2 , so that on the displacement of the block l^1 , l^2 the worm or the screw-wheel f^2 is also displaced along the shaft c .

The guide sleeves i^1 , i^2 for the parallel tensioning bars and compressive bars are each provided on their front ends with an eccentrically mounted coiler o^1 and o^2 respectively. Each coiler consists of a screw inserted in the front end of the sleeve in question and a roller preferably of hardened steel, surrounding the outer portion of the screw and the screw head. The purpose of these drivers is to engage the ends of the cross-wires, which are applied from above or below across the pair of the parallel bars passing through the sleeves i^1 , i^2 with the ends of the cross-wires projecting beyond the bars and coil them round these bars. When, for example, a cross-wire is applied from above to the bars carried by the sleeves i^1 and i^2 , the sleeve i^1 must be rotated clockwise and the sleeve i^2 anticlockwise, so that the ends of the cross-wire are wound round the parallel bars in opposite directions. Each of the sleeves i^1 and i^2 is provided on its front end with a helicoidal surface p^1 and p^2 respectively which pitches in an opposite direction to the direction of rotation of the sleeve. On winding the ends of the cross-wire resting against this helicoidal surface round the bars carried by the sleeves i^1 , i^2 the cross-wire is pushed forward in the direction of the bars in such a manner that the turns produced in the cross-wire are placed one beside the other and do not interfere with one another.

As soon as a cross-wire has been wound round the bars carried by the sleeves i^1 and i^2 , these bars are pushed forward by hand conjointly through the sleeves i^1 , i^2 , to the extent required for the purpose of applying the next cross-wire. In cases where a larger or smaller space is required between the parallel bars of the reinforcements or the like which are to be manufactured, the block l^1 , l^2 together with the sleeve i^3 is pushed to the left or to the right by means of the rod l^3 and is locked in the position desired at any time by means of the pin or the screw l^8 .

70 I claim:

1. A machine for forming metal frames of the character designated comprising in combination, two parallel sleeves, each permitting the passage of one of the main bars, coiling rollers carried eccentrically at the ends of said sleeves and

gearing for driving said coiling rollers in opposite directions.

2. A machine for forming metal frames of the character designated comprising in combination, two parallel sleeves, each permitting the passage of one of the main bars, coiling members carried at the ends of said sleeves, gearing for driving said coil members in opposite directions, and a limb attached to one of said sleeves and engaging the driving gear therefor, said limb causing said driving gear to move transversely when said sleeve is so moved.

3. A machine for forming metal frames of the character designated comprising in combination a casing, a shaft having bearings in the upper part of said casing and having one end projecting therefrom, a driving handle on said projecting end, gear wheels mounted on said shaft in sliding relation, two parallel sleeves mounted in said casing below said shaft and at right angles thereto, coiling means carried by said sleeves and gear wheels carried by said sleeves and in engagement with the gear wheels before mentioned, said gear wheels being so arranged that the sleeves are rotated in opposite directions.

4. A machine for forming metal frames of the character designated comprising in combination two parallel sleeves, each permitting the passage of one of the main bars, coiling members carried at the ends of said sleeves, a driving shaft transverse to said sleeves, toothed gearing between for driving said coiling members in opposite directions from said driving shaft, a transverse guide for one of said sleeves parallel to said driving shaft, and means for moving said sleeve in said transverse guide and for causing the driving gear to move therewith and to slide along said driving shaft.

5. A machine for forming metal frames of the character designated comprising in combination two parallel sleeves, each permitting the passage of one of the main bars, coiling members carried at the ends of said sleeves, a driving shaft transverse to said sleeves, toothed gearing between for driving said coiling members in opposite directions from said driving shaft, a transverse guide for one of said sleeves parallel to said driving shaft, a handle connected to one of said sleeves for moving said sleeve in said transverse guide, and means for locking said handle in adjusted position.

6. A machine for forming metal frames of the character designated comprising in combination two parallel sleeves, each permitting the passage of one of the main bars, coiling members carried at the ends of said sleeves, a driving shaft transverse to said sleeves, toothed gearing between for driving said coiling members in opposite directions from said driving shaft, a transverse guide for one of said sleeves parallel to said driving shaft, and removable liners in said sleeves to accommodate main bars of varying diameter.

7. A machine for forming metal frames of the character designated comprising in combination two parallel sleeves, each permitting the passage of one of the main bars, coiling members carried at the ends of said sleeves, a driving shaft transverse to said sleeves, toothed gearing between for driving said coiling members in opposite directions from said driving shaft, a transverse guide for one of said sleeves parallel to said driving shaft, a casing enclosing said sleeves and driving shaft, a guide formed as an 150

opening in said casing, and a block carrying one of said sleeves and adapted for transverse movement in said guide.

8. A machine for forming metal frames comprising a casing, coiling means carried stationary in said casing, a second coiling means slidably mounted in said casing, means associated with

each of said coiling means to receive a frame bar about which a wire may be coiled by said coiling means, said second coiling means being adjustable with relation to the first, and stationary coiling means to vary the distance between the frame bars.
